ABSTRACT

The present invention relates to novel flavourings, in particular certain dioxolane derivatives and a process for the manufacture thereof, to flavouring compositions containing said derivatives and with a method of imparting a flavour to materials by means of said derivatives.

4 Claims, No Drawings

4-N-BUTYROXYMETHYL-1,3-DIOXOLANES

FIELD OF THE INVENTION

This invention relates to the fields of flavourants and substituted dioxolanes.

DESCRIPTION OF THE PRIOR ART

British Patents Nos. 1,195,909; 1,166,636 and 559,451 are the closest prior art known to the inventor; but none of these patents discloses compounds having the striking flavour and properties of the compounds of this invention.

SUMMARY OF THE INVENTION

The dioxolane flavourants provided by the present invention have the following general formula

wherein R¹ represents a straight-chain or branched-chain alkyl or alkenyl group containing 2-6 C-atoms, R² represents a hydrogen atom or an alkyl group containing 1-3 C-atoms and R³ represents a grouping of the formula

(a)

or

(b)

in which R⁴ represents a hydrogen atom or a hydroxy group and R⁵ and R⁶ each independently represent a hydrogen atom or a straight-chain or branched-chain alkyl or alkenyl group containing up to 6 C-atoms.

According to the process provided by the present invention, the dioxolane derivatives of formula I above are manufactured by either

a. cyclising a diol of the general formula

(II)

with a carbonyl compound of the general formula

(III)

or

b. esterifying the primary alcohol group of a compound of the general formula

with an acid of the general formula

(V)

5 or a functional derivative thereof; in which formulae R¹, R² and R³ have the significance given earlier.

DESCRIPTION OF THE PREFERRED EMBODIMENTS

10 As aforementioned, in the general formula I of the novel flavourants of this invention:

R¹ represents a straight-chain or branched-chain alkyl or alkenyl group containing 2-6 C-atoms. Examples of such groups are: ethyl, n-propyl, isopropyl, n-butyl, isobutyl, secbutyl, tertbutyl, n-pentyl and n-hexyl (including their structural isomers), and 1'-propenyl, 1'-methyl-1'-propenyl and 2'-propenyl. R¹ preferably represents the n-propyl group, in which case the derivatives of formula I are butyric acid esters.

15 R² represents a hydrogen atom or an alkyl group containing 1-3 C-atoms, i.e. the methyl, ethyl, n-propyl or isopropyl group. In the preferred derivatives of formula I, R² represents a hydrogen atom or the methyl group.

R³ represents a grouping of formula (a) or (b). Examples of alkyl and alkenyl groups which may be present on said groupings as a substituent denoted by R⁵ and/or R⁶ are alkyl groups containing 1-6 C-atoms such as those mentioned earlier in connection with R¹ and R² and alkenyl groups containing 2-6 C-atoms such as vinyl, 1'-and 2'-propenyl, 1'-butenyl etc. In the preferred derivatives of formula I, R³ represents the 1'-propenyl group (—CH=CH—CH₃) or the 1'-hydroxyethyl group (—CHOH—CH₃).

25 The dioxolane derivatives of formula I provided by the present invention are distinguished, as has surprisingly been found by particular flavour properties, on the basis of which they can be used as flavourings in aroma compositions. Of particular interest is the buttery aroma of certain of the derivatives of formula I, particularly of the following three derivatives:

2-(1'-propenyl)-4-n-butyroxyethyl-dioxolane [formula I: R¹ = —CH₂—CH₂—CH₃, R² = H, R³ = —CH=CH—CH₃];

45 2-methyl-2-(1'-hydroxyethyl)-4-n-butyroxyethyl-dioxolane [formula I: R¹ = —CH₂—CH₂—CH₃, R² = H, R³ = —CH=CH—CH₃];

50 2-(2'-methyl-propyl)-4-n-butyroxyethyl-dioxolane [formula I: R¹ = —CH₂—CH₂—CH₃, R² = H, R³ = —CH₂—CH(CH₃)₂]. The latter derivative also displays an interesting cocoa-like aroma. Other derivatives of formula I have interesting fruity aroma notes and can therefore be employed as components of fruit aromas, for example of strawberry type aromas.

55 The concentration of the dioxolane derivatives of formula I in aroma compositions such as butter or fruit aromas can lie between about 0.01 and 100 parts per thousand, but it preferably lies in the range of 0.1 to 10 parts per thousand. In finished products aromatized with such aroma compositions such as pastry, fruit tarts etc correspondingly lower concentrations of the dioxolane derivatives of formula I (for example 0.1 to 10 parts per million) are present.

60 The following Examples illustrate aroma compositions containing a dioxolane derivative of formula I.

EXAMPLE I

1 part by weight of 2-(1'-propenyl)-4-n-

butyroxymethyl-dioxolane is added to an aroma composition A consisting of:

diacetyl	520	parts by weight
butyric acid	370	..
lactic acid	50	..
vanillin	40	..
butyric acid ethyl ester	10	..
heliotropin	5	..
benzaldehyde	5	..
	1000	parts by weight

The composition B thus obtained is unequivocally superior from the point of view of flavour to composition A. That is to say, if pastry is manufactured with compositions A and B using an amount of said compositions of 50 g per 1000 kg of dough (0.5%), the pastry aromatized with composition B displays an unequivocally finer butter flavour.

EXAMPLE II

10 parts of 2-methyl-2-(1'-hydroxyethyl)-4-n-butyroxy-methyl-dioxolane are added to the butter aroma composition A set forth in Example I. The composition C thus obtained is used for aromatizing pastry in a dosage of 0.5%. The pastry aromatized with composition C is unequivocally superior from the point of view of flavour to that aromatized with 0.5% of composition A.

In embodiment (a) of the process, an aldehyde or ketone of formula III is acetalized or ketalised in a manner known per se with a diol of formula II, namely an α -monoester of glycerine, with cyclisation to a dioxolane derivative of formula I. As usual, the acetalisation or ketalisation is advantageously carried out by heating the mixture of the components in the presence of a solvent and expediently in the presence of an acidic catalyst with continuous removal of the water which forms, for example, by means of an entraining agent.

As the entraining agent there can be used solvents which are usually employed for this purpose such as, for example, aromatic and saturated aliphatic hydrocarbons (e.g. benzene, toluene or n-pentane). Such solvents facilitate the continuous removal of the water (which forms during the cyclisation) by azeotropic distillation.

As acidic catalysts there can be used the substances which are usually used for acetalisations or ketalisations; for example, mineral acids such as sulphuric acid, phosphoric acid and perchloric acid, strong organic acids such as trichloroacetic acid or p-toluenesulphonic acid and Lewis acids such as, for example, boron trifluoride etc.

In embodiment (b) of the process, the primary alcohol group of a cycloacetal or cycloketal alcohol of formula IV is esterified to yield a dioxolane derivative of formula I with an acid of formula V or with a functional derivative of such an acid (e.g. the anhydride or a halide such as the chloride). The esterification can be carried out according to methods known per se; for example, by acylation according to Schotten-Baumann in the presence of a base, or by reaction of an alcohol of formula IV with an acid of formula V or its anhydride in the presence of an acidic catalyst and expediently in the presence of a solvent and with continuous removal of the water which forms. As acidic catalysts there can be used those mentioned earlier in connection with embodiment (a) of the process.

The starting materials of formula II, III, IV and V can, insofar as they are not known, be prepared according to methods known per se.

2,4-Di- and 2,2,4-trisubstituted dioxolane derivatives such as those of formula I hereinbefore can theoretically exist in a cis and a trans form (see, for example, J. Chem. Soc. 1970, 263). It will be understood that formula I is meant to include the cis and trans forms as well as mixtures of these two forms. The derivatives of formula I manufactured in accordance with the process provided by this invention are obtained mostly as cis-trans isomer mixtures with about the same amounts of cis and trans forms.

The following Examples illustrate the process provided by the present invention.

EXAMPLE 1

48.6 g of glycerin- α -mono-n-butyrate, 14.4 g of n-butyraldehyde and 150 ml of hexane are boiled in the presence of 0.1 g of p-toluenesulphonic acid for 24 hours under a water-separator. The mixture obtained after expulsion of the theoretically expected amount of water is cooled and carefully washed neutral. After drying over potassium carbonate, the solvent is distilled off and the residue (42 g) fractionally distilled. The 2-propyl-4-butyroxymethyl-dioxolane which is obtained in a yield of 87% boils at 80°C 0.2 mmHg: $n_D^{20} = 1.4315$.

EXAMPLE 2

300 g of glycerin- α -mono-n-butyrate and 150 g of crotonaldehyde are dissolved in 1200 ml of benzene and boiled in the presence of 4 g of p-toluenesulphonic acid under a water-separator. After cooling the mixture, it is transferred into a separating funnel and washed neutral with water, 5% sodium hydrogen carbonate solution and water. The solvent is subsequently distilled off and the residue fractionally distilled on a packed column. The 2-(1'-propenyl)-4-n-butyroxymethyl-dioxolane which is obtained in a yield of 75% boils at 101°-102°C 0.4-4 mmHg: $n_D^{20} = 1.4520$.

EXAMPLE 3

45 200 g of acetyl methyl carbinol, 366 g of α -glycerin-n-monobutyrate, 1300 ml of benzene and 8 g of p-toluenesulphonic acid are mixed in a 4-necked stirring flask provided with a water separator and boiled at reflux with stirring. After 5 hours, the amount of water expelled amounts to about 40 ml, corresponding to an approximately complete reaction. The mixture is cooled and poured into 500 ml of saturated aqueous sodium hydrogen carbonate solution. The benzene solution is separated off in a separating funnel and washed thoroughly with water. After drying for a short time, the benzene is distilled off and the residue fractionated on a packed column. There are thus obtained 182 g of 2-methyl-2-(1'-hydroxyethyl)-4-n-butyroxymethyl-dioxolane of boiling point 104°-106°C 0.2 mmHg ($n_D^{20} = 1.4487$) in the form of a mixture of 2 stereoisomers in the ratio of ca 1:1.

EXAMPLE 4

65 23 g of 2-(1'-propenyl)-4-hydroxymethyl-dioxolane are mixed together with 12.5 g of absolute pyridine and 250 ml of chloroform in a suitable reaction vessel and the mixture is cooled to -10°C. 18 g of n-butyric acid

chloride are then added dropwise over a period of 20 minutes and the resulting mixture is stirred for a period of 5 hours, the temperature being allowed to rise gradually to room temperature. The mixture is then washed

and formula of this material (see Example 11 of Table), as well as those of other dioxolane derivatives encompassed by this invention, are given in the accompanying Table:

Table

Example	R ¹	R ²	R ³	Bp(°C)/Torr	n _D ²⁰
5	—CH ₂ CH ₂ CH ₃	—CH ₃	—CH ₂ CH ₃	74°/0.2	1.4364
6	—CH ₂ CH ₂ CH ₃	—H	—CH ₂ CH ₂ CH ₃	80°/0.2	1.4315
7	—CH ₂ CH ₂ CH ₃	—H	—(CH ₂) ₄ CH ₃	92°/0.02	1.4401

14	—CH(CH ₃)CH ₂ CH ₃ CH ₃	—	—CHOH—CH ₃	101-103°/0.4	1.4489
15	—C(CH ₃)=CHCH ₃ H	—H	—CH=CHCH ₃	97°/0.05	1.4766
16	—CH(CH ₃)CH ₂ CH ₃ H	—H	—CH=CHCH ₃	108-109°/1	1.4512

with sodium hydrogen carbonate solution and water, dried, freed from the solvent and distilled. There are thus obtained 28g of 2-(1'-propenyl)-4-n-butyroxyethyl-dioxolane of boiling point 90°-92°C/0.05 mmHg; n_D²⁰ = 1.4535.

As will be understood by organic chemists, other dioxolane derivatives encompassed by this invention may be made by the methods of Examples 1-3. For example, by substituting 20 g of β -methyl-m-butyryl-(isovaler-)aldehyde in place of the 14.4 g of n-butyraldehyde used in Example 1, 2-(2'-methyl-propyl)-4-n-butyroxyethyl-dioxolane is obtained. The properties

20 What is claimed is:

1. A compound selected from the group consisting of 2-(1'-propenyl)-4-n-butyroxyethyl-dioxolane; 2-methyl-2-(1'-hydroxyethyl)-4-n-butyroxyethyl-dioxolane and 2-(2'-methyl-propyl)-4-n-butyroxyethyl-dioxolane.
2. 2-(1'-Propenyl)-4-n-butyroxyethyl-dioxolane.
3. 2-Methyl-2-(1'hydroxyethyl)-4-n-butyroxyethyl-dioxolane.
4. 2-(2'-Methyl-propyl)-4-n-butyroxyethyl-dioxolane.
